R. LINDBLOOM.

POWER TRANSMISSION.

APPLICATION FILED AUG. 7, 1918.

1,340,833.

Patented May 18, 1920.

UNITED STATES PATENT OFFICE.

RALPH LINDBLOOM, OF ST. PAUL, MINNESOTA.

POWER TRANSMISSION.

1,340,833.

Specification of Letters Patent. Patented May 18, 1920.

Application filed August 7, 1918. Serial No. 248,752.

To all whom it may concern:

Be it known that I, RALPH LINDBLOOM, a citizen of the United States, residing at St. Paul, in the county of Ramsey and State of Minnesota, have invented a new and useful Improvement in Power Transmissions, of which the following is a specification.

This invention relates to the transmission of power in connection with self propelled vehicles for actuating a hoist for tilting and unloading the contents of a body by the same power unit which is employed for propelling the vehicle. More particularly this invention relates to the particular manner and construction employed for operating the hoist by the main drive shaft which is revolved by the power unit. The primary object of the invention is to provide simple and inexpensive construction for accomplishing the results stated, and to these ends my invention comprises the features of construction and combination of parts herein-after particularly described and claimed.

In the accompanying drawing forming part of this specification, Figure 1 is a typical side elevation of an automobile truck, portions of the structure being broken away and in section for the purpose of more clearly illustrating the invention; Fig. 2 is a longitudinal section of a detail, showing the clutch mechanism, and Fig. 3 is a cross section taken on the line X—X of Fig. 2.

In the drawing let A indicate a body frame of an automobile truck, B the usual power unit, C a detail of the usual body which is arranged to tilt upwardly and rearwardly to dump the contents thereof. Arranged on the body is an upwardly extending hydraulic hoist D containing the usual ram 2 and having a liquid circulating propelling pump 3 connected by suitable ducts, so that when the pump is operated it is adapted to propel the fluid medium in the hoist and force the ram upwardly to effect the tilting of the body in the usual manner. Carried by the upper end of the ram 2 are the usual sheave pulleys 4 over which the hoisting cable 5 travels, the ends of said cable being attached to the depending arms 6 secured to the body and the intermediate portion of the cable passing around a stationary compensating sheave 7 journaled on the cylinder 8 of the hoist. The pump 3 is of ordinary gear type and has a main drive shaft 9 upon which is mounted a sprocket

wheel 10, over which a chain belt 11 travels to drive the pump.

Extending rearwardly from the power generating unit B is a longitudinal drive shaft, which is made in two longitudinal sections 12 and 13, the forward section 12 extending rearwardly and being driven either in forward or reverse directions through the operation of the usual planetary change speed and reverse mechanism E, which is controlled by the operation of the foot pedal 14 in the usual manner. The rearward end of the forward section 12 of the drive shaft and the forward end of section 13 meet approximately and are freely joined in alinement by the bearing sleeve 15, which is splined to section 12 by the feather or key 16 and revolvably united with the adjacent end of the shaft section 13, so that said sections may revolve independently of each other. The rearward end of the shaft section 13 is connected by the gearing 17 with the rear jack shaft 18 to drive the latter in the usual manner, a suitable gear housing 19 of usual construction being employed to which the rearward end of a sleeve 20 around the section 13 of the shaft is secured by bolts 21 or other suitable means. Arranged over the adjacent ends of the shaft sections 12 and 13 is a yoke 22, which serves to assist in supporting said sections and the transmission parts to be hereinafter described. The forward end of the sleeve 20 is seated in the rearward end of said yoke and the forward end of the section 13 is journaled in the bearing sleeve 15 formed by the yoke. The forward shaft section 12 is surrounded by a sleeve 24 seated in the housing 25 of the main transmission E and in the forward end of the yoke 22. By this construction, the shaft sections are caused to revolve in alinement and are substantially supported for operation either independently or together.

Mounted upon the bearing sleeve 15 is a suitable clutch member 26, which is slidably joined to said sleeve to revolve therewith and to slide longitudinally thereon by the feathers or keys 27. This clutch member is formed with concentric grooves 28 extending longitudinally therethrough, which are adapted on one side of the clutch to receive the teeth 29 of the driven clutch member 30 in one extreme position of the member 26 and on the other side to receive the teeth 31

of the driven clutch member 32 in the opposite extreme position of member 26. When the member 26 is in neutral position, it is entirely out of engagement with the 5 teeth 29 and 31 and neither of said members 30 and 32 is driven. The driven clutch member 30 is rigidly secured to the driven section 13 of the shaft by the key 33 and the driven member 32 is revolvably mounted free 10 of the coupling 15 in the collar 34, which is carried by the yoke on the inwardly projecting arms 35. The collar 34 is arranged concentrically about the axis of the shaft, so that the member 32 will revolve evenly 15 about said axis. The driven member 32 has secured to its outer end a driving sprocket 36, over which the chain belt 11 travels, and by which power from the drive shaft is transmitted to the pump shaft 9 to operate 20 said pump. Journaled in the channel 37 concentrically about the axis of the shaft is a collar 38, said collar being formed with trunnions 39, which are journaled in trunnion arms 40 and 41. These arms are secured to the pin 42 which is journaled through the yoke, slots 43 being provided so that by swinging the trunnion arms the 25 clutch driving member 26 is shifted forwardly or backwardly on the coupling 15 into and out of clutch engaging positions. One of the trunnion arms 40 depends below one of the trunnions, and its lowermost end is coupled by a connecting rod 44 with a shifting handle 45, which is pivoted between 30 its ends at 46 on the frame A of the truck.

In operation when the lever 45 is in median position, the clutch driving member 26 stands out of engagement between the clutch driven members 29 and 32. When it 40 is desired to operate the truck to propel the same, the upper end of the lever 45 is tilted forwardly, causing the clutch driving member 26 to engage and drive the clutch driven member 30 and transmit power from the 45 driving member of the shaft to the driven member. When it is desired to operate the hoist and tilt the body C into dumping position, the lever 45 is reversed to extreme position causing the clutch driving member 50 26 to disengage the driven member 30 and after passing median position to engage the clutch driven member 32, causing power to be transmitted from the driving member of the shaft to the pump shaft 9 and propel 55 the fluid medium contained in the hoisting cylinder upwardly against the ram to raise the latter. The reversal of the pump to lower the ram is accomplished by the reversal of the driving member 12 of the main 60 driving shaft through the operation of the reversing mechanism E and the manipulation of its foot lever 14 in the usual manner.

The transmission mechanism for operating the pump or other external device to be 65 driven by the main drive shaft of the vehicle

is very simple and effective in operation and provides an effective device for accomplishing the results attained.

In accordance with the patent statutes, I have described the principles of operation 70 of my invention, together with the apparatus which I now consider to represent the best embodiment thereof, but I desire to have it understood that the construction shown is only illustrative, and that the invention can be carried out by other means 75 and applied to uses other than those above set forth within the scope of the following claims.

Having described my invention, what I 80 claim as new and desire to protect by Letters Patent is:

1. Power transmitting mechanism, comprising, in combination, a drive shaft having driving and driven sections in longitudinal alignment, and having abutting ends, a coupling sleeve secured to one of said sections and revolvably connected with the other, a yoke supported over said coupling sleeve, a driving clutch element shiftably 85 mounted upon said coupling sleeve and secured thereto to be revolved, a driven clutch element revolvably mounted upon said yoke free of said coupling sleeve and adapted to be engaged and driven by said driving 90 clutch element, another driven clutch element carried by said driven section of said shaft adapted to be engaged by said clutch driving element, means for shifting said driving clutch element into engagement with 95 either of said driven clutch elements and means coupled with said independently driven clutch element to be driven thereby.

2. Power transmitting mechanism, comprising, in combination, with a self propelled vehicle having a drive shaft formed with driving and driven sections in longitudinal alignment, and having their ends abutting, a pump mounted upon said vehicle to be driven by said shaft, a clutch interposed between said abutting sections of said shaft having a driving element coupled to said driving section and a pair of driven elements with either of which said driving clutch element is movable into driving connection, one of said driven clutch elements being connected with the driven section of said shaft and the other having a driving connection with said pump to operate the latter and means for shifting said driving 110 clutch element into and out of clutch engaging positions.

3. Power transmission mechanism, comprising, in combination with a self propelled vehicle having a main driving shaft 115 reversibly driven and provided with driving and driven sections in longitudinal alignment, and having their ends abutting, a yoke over the abutting ends of said shaft sections, a coupling sleeve united to one of said shaft 120 sections and secured to the other to be revolved, a driving clutch element shiftably mounted upon said coupling sleeve and secured thereto to be revolved, a driven clutch element revolvably mounted upon said yoke free of said coupling sleeve and adapted to be engaged and driven by said driving 125 clutch element, another driven clutch element carried by said driven section of said shaft adapted to be engaged by said clutch driving element, means for shifting said driving clutch element into engagement with either of said driven clutch elements and means coupled with said independently driven clutch element to be driven thereby.

sections and revolvably connected with the other, a driving clutch element slidably mounted upon said coupling sleeve, a driven clutch element united to the driven section 5 of said shaft and with which said driving clutch element is adapted to connect, another driven clutch section with which said driving clutch element is adapted to connect journaled in said yoke free of said coupling 10 sleeve, said last mentioned driven clutch sec-

tion having power transmitting mechanism connected thereto to be operated thereby and means hung from said yoke and operable by the driver for shifting said driving clutch element into and out of clutch engaging positions. 15

In testimony whereof I have signed my name to this specification.

RALPH LINDBLOOM.
